UNITED STATES PATENT OFFICE.

A. REED CONNER, OF CYNTHIANA, KENTUCKY.

DESIGN FOR A FLAG.

SPECIFICATION forming part of Design No. 35,985, dated August 5, 1902.

Application filed June 9, 1902. Serial No. 110,935. Term of patent 7 years.

To all whom it may concern:

Be it known that I, A. REED CONNER, a citizen of the United States, residing at Cynthiana, in the county of Harrison and State of Kentucky, have invented a new, original, and ornamental Design for Flags; and I do hereby declare the following to be a full, clear, and exact description of the invention, such as will enable others skilled in the art to which it appertains to make and use the same.

This invention relates to a novel and unique design for a flag, banner, badge, standard, or ensign, substantially as shown in the accompanying facsimile-drawing, which represents the flag of rectangular shape having triangular corners of contrasting color, such as purple. A diamond-shaped space is located central of the flag, and bars or stripes of contrasting color—as, for instance, yellow and white—extend diagonally across the flag in

parallel and alternate relation, being intersected by the diamond-shaped space. The pictorial representation of an aristocratic negro occupies the center of the diamond-shaped space. The representation of a chicken appears at the lower corner, an opossum at the right-hand corner, and a watermelon at the left-hand corner of the said diamond-shaped space.

Having thus described the invention, what is claimed as new is—

The ornamental design for a flag, substantially as herein shown and described.

In testimony whereof I affix my signature in presence of two witnesses.

A. REED CONNER. [L. S.]
